UNITED STATES PATENT OFFICE.

MARVIN L. ECKHART, OF ATTICA, INDIANA, ASSIGNOR TO NATIONAL CAR COUPLER CO., OF CHICAGO, ILLINOIS, A CORPORATION OF ILLINOIS.

CAR-COUPLING.

1,378,098.

Specification of Letters Patent. Patented May 17, 1921.

Application filed January 30, 1920. Serial No. 355,062.

To all whom it may concern:

Be it known that I, MARVIN L. ECKHART, a citizen of the United States, residing at Attica, in the county of Fountain and State 5 of Indiana, have invented certain new and useful Improvements in Car-Couplings, of which the following is a specification, reference being had to the accompanying drawings, and to the reference characters marked 10 thereon, which form a part of this specification.

This invention relates to improvements in car couplers, and more particularly to what might be termed radial couplers for mine 15 cars, which latter are usually operated upon narrow gage tracks and around very sharp curves.

The various types of couplers in use on surface and standard gage tracks are not 20 applicable to mine cars of relatively narrow width and operated around sharp curves, for reasons well known. Therefore, on mine 25 cars, the coupling is usually accomplished by a simple hook and chain and by manual effort. They are not automatically operated. Generally, the hook, pin or clevis, to which 30 the chain link is attached in coupling two mine cars together, is positioned centrally of the car end, and in a pocket or recess formed 35 by bumpers projecting from the end sill of the car. This construction affords opportunity for accidents, which not infrequently happen to the operator when coupling and uncoupling the cars. Moreover, the bumpers, which are required for obvious reasons, 40 necessarily project from the side margins of the car ends a considerable distance and this interferes with the operation of such cars around curves as sharp as are required in many parts of almost every mine.

It is the object of my invention to produce a car coupler which will act automatically to couple two cars together; which may be uncoupled from a point at the side of the 45 cars; which will provide the necessary bumpers upon the car ends; which will enable the coupled cars of a train to be swung around the sharpest curves without uncoupling; which will simplify and cheapen 50 mining car construction; which will be applicable in principle to all types of mining cars, requiring slight and minor modifications in the means of attachment only for the

cars of different types; which may be applied to existing types of cars by making 55 the minimum alterations therein and which will be strong, durable and efficient in use, reduce the cost of repairs and upkeep to a minimum and finally, but not least, reduce 60 the possibility of accidents to the operators to a negligible quantity.

These and other objects of my invention will be more fully appreciated as I proceed with my specification.

In that form in which I have chosen to 65 illustrate my invention in the drawings:

Figure 1 is an end view of a car, partially in section, to which the coupling embodies my invention, is applied.

Fig. 2 is a top plan view of one end of 70 the car.

Fig. 3 is a top plan view, enlarged, and partially in section, of the coupling, the section being in the horizontal plane indicated by the dotted line 3—3 of Fig. 4. 75

Fig. 4 is an enlarged, vertical, transverse sectional view on the plane indicated by the dotted line 4—4 of Fig. 3.

Fig. 5 is an enlarged view of the coupling, in side elevation, showing a part of the car 80 floor timbers to which it is bolted.

Fig. 6 is an enlarged, vertical, longitudinal sectional view of the housing with the interior parts removed, the section being taken in the plane indicated by the dotted 85 line 6—6 of Fig. 2.

Fig. 7 is a similar sectional view with the interior parts in position.

Fig. 8 is a perspective view of the removable swinging plate on which the coupler 90 arms are secured.

Fig. 9 is a perspective view of the unlocking lever.

Fig. 10 is a view similar to that of Fig. 3, showing the parts in a different position. 95

Fig. 11 is a vertical, sectional view of a detail, the section being taken on the dotted line 11—11 of Fig. 3.

Fig. 12 is a vertical sectional view taken in the plane indicated by the dotted line 100 12—12 of Fig. 10, showing the unlocking lever in a different position from that illustrated in Fig. 7.

The car, designated as a whole by the letter A, may be of any ordinary or conventional type, comprising vertical side walls 105

10, end walls 11, inclined bottom 12, and a floor 13, all supported upon axles 14 carrying track wheels 15. Beneath the lower part of the end walls 11 is a transverse beam 5 or timber 16.

B indicates as a whole, the housing of my improved coupler, comprising upper and lower horizontally disposed plates 17, 18, respectively, integral with and spaced apart 10 by a vertically disposed rear wall 19, and side walls 20, 20. Projecting outwardly from the rear and side walls 19, 20, is a horizontally disposed flange plate 21, provided with suitable bolt holes 22 through 15 which may be passed the bolts 23 used in securing the housing B to the car floor 13. The flange plate 21 is preferably so located as to afford space for locating one or more (in this instance, two) strengthening ribs 20 24 beneath it.

The top and bottom plates 17 and 18 of the housing B, forward of the side walls 20, 20, are rounded and are provided with marginal downwardly projecting flange walls 25, 26, respectively. These rounded flanged portions of the plates 17, 18, may properly be designated the coupler head. It will be noticed that between the top surface of the bottom plate 18 and the lower margin of 25 the flange 25 (see Figs. 6, 11 and 12) there is a considerable space which I have indicated by the letter C, which space affords 30 means for the insertion of the coupler parts presently to be described, and means for the 35 operative movement of said parts when the device as a whole is in use on a car.

Projecting downwardly from the under side of the plates 17, 18, are apertured bosses 27, 28, respectively, one shorter than 40 the other (see Fig. 6), the lower face of the boss 27 being in the horizontal plane of the lower margin of the flange 25. The aperture 29 extends through the boss 28 and the plate 18. The aperture 30, in vertical alignment with the aperture 29, extends through the boss 27 and communicates with an enlarged aperture 31 in the plate 17. A pivot pin 32 extends through the apertures 29, 30, its head 33 resting in the aperture 31 and a 45 nut 34 on its lower end serving to bear 50 against the boss 28 and lock the pin 32 in place. It will be noticed that the vertical axis of the apertures 29 and 30 is located to intersect the longitudinal median line of 55 the housing B.

D designates, as a whole, a movable fulcrum plate, triangular in shape, and having in its front end a vertically disposed aperture 35 through which the pivot bolt 32 extends. The fulcrum plate D rests upon the plate 18 and its thickness is such as to clear 60 the lower edge of the flange 25, so said plate may freely swing in a horizontal plane about the pin 32 as a pivot. A weight saving cavity is designated d. In each corner 65

of its rear portion are vertical apertures 36, 36, to afford bearings for pivot pins 37, 37. In each side of the plate D is a horizontally disposed slot 38, 38, for a purpose to be presently stated.

E designates, as a whole, a casting which I call a coupling knuckle and of which two are required. Each knuckle comprises an irregular shaped body 39, a vertically apertured, pivoting flange 40, and a knuckle arm 41, the latter having a coupling head 42 on its end. The thickness of the body 39 is such as to permit of its insertion in the space C of the housing, and the thickness of the flange 40 is such as to permit said flange 75 to be inserted in the slot 38. The pin 37 passes through the apertured flange 40 and the depth of the said slot 38 is such that the knuckle E may be moved laterally with respect to the fulcrum plate D by swinging 80 upon the pin 37 as a pivot. The arm 41 and the head 42 are relatively thicker than the body 39, the thickness, in the form illustrated, being substantially equal to the distance from the top of the plate 17 to the 85 bottom of the flange 26.

The margin of the body 39 from which the flange 40 extends is tapered or inclined upwardly and inwardly, as shown at 43 in Figs. 3 and 10, thus conforming to the triangular contour of the fulcrum plate D to which the two knuckles E, E, are pivotally secured.

The plate D and the two knuckles are normally "centered" with respect to the housing B by the following means: A spring 44 is coiled between its ends 45, 45, around and is mounted upon the boss 27. On each end 45 of said spring is a bushing 46 which has frictional contact against the inclined rear margin of a lug 47 on the body 39. Intermediate the coiled central part of the spring 44 and its two ends 45, 45, the spring is bent upwardly, as shown at 48, to contact and bear against the face of a lug 49 which projects downwardly from the under side of the plate 17. Thus it will be readily seen that whatever force or pressure is exerted upon one of the knuckles E will be communicated to the plate D through pivotal connections 40, 37, and similarly to the opposite knuckle, both knuckles E, E, and the plate D, swinging or moving together as a unit around the fixed bolt 32 as a pivot. Relative motion of the knuckles E, E and 100 the plate D, may occur and, while the spring 50 exerts tension upon the knuckles E, E, to hold them together on the plate D, the spring 44 exerts tension to hold the jaws 105 together in the normal position, as illustrated in Fig. 3. When the jaws are swung out of normal position, as illustrated in Fig. 10, the bushing 46 carried on one end of the spring 44 will contact, while the other bushing 46 carried on the other end of the spring 110 115 120 125 130

44, will be out of contact. Thus there will be constant tension by one end of said spring 44 to return the jaws to their normal closed position as soon as the fulcrum plate and jaws, as a unit, are free to so return.

Means are provided, however, for spreading the knuckles E, E, apart, and for returning them to their normally closed position, the latter position being shown in Fig.

10 3, and the spread apart position in Fig. 10, said means comprising a spring 50 and an unlocking lever L. The spring 50 is positioned in two alined recesses 52, one in each knuckle body 39 and its ends 53 are wrapped 15 around or otherwise secured to vertically positioned rivet pins 54, one in the inner end of each recess 52. The tension of this spring 50 tends to hold the proximate margins 55, 55, of the two knuckles E, E, together, or in the normal position shown in 20 Fig. 3. In said Fig. 3, the heads 42 of the knuckles E, E, of two cars are shown in operative engagement, the one set of knuckles being illustrated by dotted lines.

25 The unlocking lever L, see Fig. 9, comprises an operating arm 51 which is preferably apertured at 56 for engagement with a link, cord, or chain (not shown) whereby the arm 51 may be actuated, and a right angled shank 57 carrying on its upper end portion a cam shaped elongated head 58 and having a flanged end 59. Located between the recess 52 and the upper part of the inner margin 43 of the body 39 is a 35 shallow recess 60 having a straight bottom and curved end walls as shown. When the two knuckles E, E, are in their normally closed position, these recesses 60, 60, register and together form an elongated slot with 40 straight parallel sides and rounded ends as shown by the dotted lines in Fig. 3. The head 58 of the lever L has correspondingly straight parallel sides and rounded ends, adapted to fit in said elongated slot. It will 45 be observed that the latter is located with its longitudinal or major axis parallel with the abutting side margins 67 of the body 39, and as a consequence, said margins will be moved apart whenever the lever L is turned 50 so that the rounded ends of the head 58 bear against the straight sides of the slot; the head 58 being longer than it is wide, said rounded ends act as cams to spread the 55 knuckles E, E, apart against the tension of the spring 50.

To retain the lever L in its proper position, and to prevent it from falling out through an entrance opening 61 in the lower plate 18, a marginal flange or rib 62 is 60 formed on the body 39 for the lever end 59 to rest upon. And, to further insure proper operative relation of the unlocking lever L and the knuckles E, E, a downwardly directed segmental rib 63 projects from the 65 under side of the plate 17, the lower margin

of which is adjacent to the upper surface of the lever end 59. This rib 63, as shown in dotted lines in Fig. 3, is formed on a radius of a circle, having the axis of the bolt 32 as a center, and its length is such as to embrace the extreme limit of movement or oscillation of the knuckles E, E, and the fulcrum plate D on either side of the pivot bolt 32.

When two cars are to be coupled together, 75 the knuckles E, E, of the adjacent ends are normally in the positions shown in full lines in Fig. 3, in the same horizontal plane and, theoretically, truly centered. In practice, however, the lugs 49, 49, are just sufficiently 80 off the transverse center line so that the points 64 of the knuckle jaws 42 will not register, that is, will not lie in the same vertical plane, the result being that as one car is pushed closer to the other, the sides 85 65 of the jaws engage, the jaws on one car sliding on the jaws of the other car until the shoulders 66 of the jaws 42 interlock, as shown in full and dotted lines in Fig. 3. This interlocking is automatic, on account 90 of the tension spring 50, which stretches or yields as the jaws are sliding upon each other (the knuckles E, E, being spread apart by this sliding contact) and which promptly contracts the moment the shoulders 95 66 come into alinement. The cars being thus coupled together, the train may be moved along a straight or a curved track, the couplers holding firmly on the shortest of curves because the knuckles readily piv- 100 otting upon the bolts 32 conform to the curvature.

To uncouple the cars, the operator actuates the lever L on one of the cars by taking hold of the arm 51 or the link connected thereto at 56, and thus turns the cam head 58 in the slot 60. This action will tend to spread the knuckles E, E, apart, and disengages, we will say, the right hand arm 3 from the corresponding arm E on the 110 other car. As the two cars are pulled away from each other, the jaws on the left hand side will automatically shift toward the center line of the couplers into such position as will automatically permit the shoulder 66 of 115 one arm E to slip by and free from the corresponding shoulder 66 of the arm on the other car. The curvatures given to the arms 41 and their shoulders 66 are such that as these arms E, E, move toward the center 120 line, the jaws will be disengaged entirely before the two arms E, E, reach their normal position as shown in full lines in Fig. 3. In uncoupling, it is only necessary to turn the cam head 58 of one coupler.

125 It may be observed that the shape and arrangement of these arms E, E, are such that when they are engaged with the arms of the adjacent car, the cars may be turned upon a very short curve without uncoupling. 130

In practice I have demonstrated that these 5
couplers will hold and not become disengaged when the curve of the track is so short as to cause the inside corners of the adjacent car ends to meet. I regard this as an important features of my invention.

It will be noticed that the rounded plates 10
17, 18, extend well forward from the car end 11 and serve as bumpers, and as such their rounded margins permit one to rock, so to speak, about the other when two cars coupled together are going around a curve. Moreover, the width of the coupler housing B relative to the width of the car A is such 15
that curves so sharp as to cause the end corners a to almost contact on the curve, may be readily negotiated without any danger of the interlocked knuckle jaws 42, 42, becoming unlocked.

20 I would have it understood that the shape of the rear end of the housing B and of the attaching flange 21 may be varied to suit cars other than that of the car A herein illustrated, said car A being shown 25
merely as one type of car to which my improved radial coupler may be applied. Therefore, I wish it understood that I do not limit my invention to the specific details of construction herein shown and described, except as may be indicated by the 30
subjoined claims.

I claim as my invention:

1. A car coupler comprising a housing, 35
means for securing the housing to the car, a fulcrum plate pivotally mounted within the housing, a pair of fulcrum arms each pivotally secured at its rear end to said plate and provided at its outer end with a coupling jaw projecting beyond the margin 40
of the housing and means independent of the plate for operatively holding the fulcrum arms together.

2. A car coupler comprising a housing having two forwardly projecting plates 45
spaced apart, means for securing the housing to the car, a fulcrum plate pivotally mounted within the housing between said plates, a pair of fulcrum arms each pivotally secured at its inner end to said fulcrum plate and having on its other end a coupling jaw projecting outwardly through the space between the housing plates, and means upon the fulcrum arms for yieldingly holding said arms normally together.

55 3. A car coupler comprising a housing having two forwardly projecting plates spaced apart, means for securing the housing to the car, a fulcrum plate pivotally mounted within the housing between said plates, a pair of fulcrum arms each pivotally secured at its inner end to said fulcrum plate and having on its outer end a coupling jaw which projects outwardly through the space between the housing plates, means 60
65 on the fulcrum arms for yieldingly holding

them normally together and means for spreading said arms apart.

4. A car coupler comprising a housing having two forwardly projecting plates spaced apart and adapted to be secured to the car, a fulcrum plate pivotally mounted within the housing between said plates, a pair of fulcrum arms pivotally secured at one end to said fulcrum plate and having their other ends projecting outwardly through the space between the housing plates, a coupling jaw on the outer end of each fulcrum arm, means attached to the fulcrum arms for yieldingly holding said arms normally together, and means associated with the housing and fulcrum arms for centering the latter.

5. A car coupler comprising a housing having top and bottom plates spaced apart at the front of the housing to form a slot or space, said housing being adapted to be secured to the car, a fulcrum plate pivotally mounted within the housing, a pair of fulcrum arms movably connected to the fulcrum plate and projecting outwardly through and adapted to move laterally in the space between the two housing plates, a coupling jaw on the end of each fulcrum arm, yielding means attached to the fulcrum arms for holding said arms in coupling relation and means upon the housing and in coöperative relation with the fulcrum arms for holding the fulcrum plate and said arms in operative relation.

6. A car coupler comprising a housing having top and bottom plates spaced apart at the front of the housing to form a slot or space, means for securing the housing to the car, a fulcrum plate pivotally mounted within the housing, a pair of fulcrum arms 105
movably connected to the fulcrum plate and projecting outwardly through and adapted to move laterally in the space between the two housing plates, a coupling jaw on the end of each fulcrum arm, yielding means attached to the fulcrum arms for normally holding said arms in coupling relation and resilient means upon the housing and co-operatively associated with the fulcrum arms for holding the fulcrum plate and 110
115 said arms in operative relation.

7. A car coupler comprising a housing having top and bottom plates spaced apart at the front of the housing to form a slot or space, means for securing the housing to the car, a fulcrum plate pivotally mounted within the housing, a pair of fulcrum arms movably connected to the fulcrum plate and projecting outwardly through and adapted to move laterally in the space between the two housing plates, a coupling jaw on the end of each fulcrum arm, a spring 120
125
130 for normally holding said arms in coupling relation and a spring coiled between its ends and mounted upon a fixed portion of the

housing, with oppositely extending arms the end of each of which is in yielding contact with a fulcrum arm and the portions of the spring intermediate its ends and its coiled 5 part having contact with a fixed lug on the housing.

8. A car coupler comprising a housing having top and bottom plates spaced apart at the front of the housing to form a slot or 10 space, means for securing the housing to the car, a fulcrum plate pivotally mounted within the housing, a pair of fulcrum arms each pivoted at its inner end to the fulcrum plate and each having on its forward end a coupling 15 jaw which projects outwardly beyond the housing, said fulcrum arms being adapted to move laterally in the space between the housing plates, a coiled spring yieldingly connecting the fulcrum arms to hold them 20 normally together and a spring mounted upon the pivoted fulcrum plate for holding the fulcrum plate and arms in operative relation, said spring being adapted to contact in operative relation with said arms and 25 a fixed part upon the housing.

9. A car coupler comprising a housing having top and bottom plates spaced apart at the front of the housing to form a slot or space, means for securing the housing 30 to the car, a fulcrum plate pivotally mounted within the housing, a pair of fulcrum arms, the inner end of each arm being pivotally connected to the fulcrum plate, the outer end of each arm projecting outwardly 35 through and adapted to move laterally in the space between the two housing plates and being provided with a coupling jaw, a coiled spring yieldingly connecting the fulcrum arms to hold them normally together 40 and mechanism coöperating with both fulcrum arms for spreading them apart.

10. A car coupler comprising a housing adapted to be secured to a car and with vertically spaced apart plates projecting, in 45 use, forward of the car body end, a triangular shaped fulcrum plate provided with a bolt bearing aperture, laterally extending recesses in the side margins of the fulcrum plate, a pair of fulcrum arms, projecting 50 apertured lugs on the fulcrum arms adapted to fit in the lateral recesses of the fulcrum plate, pivot pins for movably securing said arms to the fulcrum plate and a spring mounted upon the housing with its 55 ends coöperating with the fulcrum arms for centering the fulcrum plate and arms.

11. A car coupler comprising a housing having two forwardly projecting plates spaced apart, said housing being adapted to 60 be secured to the car, a fulcrum plate pivotally mounted and located within the space between said plates, a pair of fulcrum arms pivotally secured at one end to said fulcrum plate, their other ends projecting outwardly 65 through the space between the housing

plates, a coupling jaw on the outer end of each fulcrum arm, a vertically arranged pivot bolt passing through the fulcrum plate and the housing about which said plate and the parts carried thereby may pivot or swing 70 in a horizontal plane, mechanism associated with the housing and the fulcrum arms for centering same, comprising a boss on the inside of the housing and a spring coiled about said boss and the spring arms projecting in opposite directions, a pair of lugs on the housing, one on either side of said boss, against which a bent part of the oppositely projecting spring arms contact, a lug on each fulcrum arm and a pair of bushings 80 one on the end of each spring arm in contact with one of said lugs.

12. A car coupler comprising a housing provided with means whereby it may be secured to a car and with horizontally spaced 85 apart plates projecting, in use, forward of the car body end, a pivotally mounted fulcrum plate located within the space between said plates, a pair of fulcrum arms pivotally secured at one end to said fulcrum plate, 90 their other ends projecting outwardly through the space between the housing plates, means connecting the fulcrum arms for yieldingly holding them normally together or in coupling relation, said means comprising a coiled spring having projecting arms, alined recesses in the proximate edges of the fulcrum arms to receive said coiled spring, and pins in the alined recesses to which the spring ends are anchored, and means for spreading the fulcrum arms apart.

13. A car coupler comprising a housing provided with means whereby it may be secured to a car and with horizontally spaced 100 apart plates projecting, in use, forward of the car body end, a pivotally mounted fulcrum plate, located within the space between said plates, a pair of fulcrum arms pivotally secured at one end to said fulcrum 105 plate, their other ends projecting outwardly through the space between the housing plates, means connecting the fulcrum arms for yieldingly holding them normally together or in coupling relation comprising a coiled spring having projecting arms, alined recesses in the proximate edges of the fulcrum arms to receive said coiled spring and pins in the alined recesses to which the 110 spring ends are anchored, means for spreading the fulcrum arms apart comprising an 115 unlocking lever.

14. A car coupler comprising a housing provided with means whereby it may be secured to a car and with horizontally spaced 120 apart plates projecting, in use, forward of the car body end, a pivotally mounted fulcrum plate, located within the space between said plates, a pair of fulcrum arms pivotally secured at one end to said fulcrum 125 plate,

plate, their other ends projecting outwardly through the space between the housing plates, means connecting the fulcrum arms for yieldingly holding them normally together or in coupling relation comprising a coiled spring having projecting arms, alined recesses in the proximate edges of the fulcrum arms to receive said coiled spring and pins in the alined recesses to 10 which the spring ends are anchored, means for spreading the fulcrum arms apart comprising an unlocking lever, a cam surface on the lever and coöperating recesses in the proximate edges of the fulcrum arms within 15 which the operating head of the lever is located.

15. A car coupler comprising a housing provided with means whereby it may be secured to a car and with horizontally spaced 20 apart plates projecting, in use, forward of the car body end, a pivotally mounted fulcrum plate, located within the space between said plates, a pair of fulcrum arms pivotally secured at one end to said fulcrum plate, their other ends projecting outwardly through the space between the housing plates, means connecting the fulcrum arms for yieldingly holding them normally 25 together or in coupling relation comprising a coiled spring having projecting arms, alined recesses in the proximate edges of the fulcrum arms to receive said coiled spring and pins in the alined recesses to which the spring ends are anchored, means for spreading the fulcrum arms apart comprising an 30 unlocking lever, a cam surface on the lever and coöperating recesses in the proximate edges of the fulcrum arms within which the operating head of the lever is located, means on the housing for limiting the insertion 35 of the unlocking lever beyond a predetermined distance and means for retaining the

lever in operative position within the housing. 40

16. A car coupler comprising a housing provided with means whereby it may be secured to a car and with horizontally spaced 45 apart plates projecting, in use, forward of the car body end, a pivotally mounted fulcrum plate, located within the space between said plates, a pair of fulcrum arms pivotally secured at one end to said fulcrum plate, their other ends projecting outwardly through the space between the housing plates, means connecting the fulcrum arms for yieldingly holding them normally 50 together or in coupling relation comprising a coiled spring having projecting arms, alined recesses in the proximate edges of the fulcrum arms to receive said coiled spring and pins in the alined recesses to which the spring ends are anchored, means for spreading the fulcrum arms apart comprising an 55 unlocking lever, a cam surface on the lever and coöperating recesses in the proximate edges of the fulcrum arms within which the operating head of the lever is located, means on the housing for limiting the insertion 60 of the unlocking lever beyond a predetermined distance and means for retaining the lever in operative position within the housing. 65

In testimony that I claim the foregoing 70 as my invention I affix my signature, in the presence of two witnesses, this 26 day of Jan., 1920.

MARVIN L. ECKHART.
